UNITED STATES PATENT OFFICE.

DANIEL A. TRACY, OF BUFFALO, NEW YORK.

STOP MECHANISM FOR TRAINS.

1,177,154.

Specification of Letters Patent. Patented Mar. 28, 1916.

Application filed July 9, 1915. Serial No. 38,833.

To all whom it may concern:

Be it known that I, DANIEL A. TRACY, a citizen of the United States, residing at Buffalo, in the county of Erie and State of New York, have invented certain new and useful Improvements in Stop Mechanism for Trains, of which the following is a specification.

My invention relates to improvements in stop mechanism for trains; the primary object being to automatically set the brakes against the wheels of the cars and locomotive of the train and also automatically shut off the steam of actuation of the throttle valve in the locomotive.

A further object of my invention is to provide means adjacent one of the rails of a track which may be actuated in conjunction with a semaphore or in conjunction with mechanism for setting a switch, and which means is adapted to cause the steam to be shut off from the locomotive cylinders and is also adapted to cause the air brake system to be brought into action for applying the brakes to the wheels of the locomotive and the wheels of the cars attached to the locomotive.

A further object of my invention is to provide means alongside the track requiring a comparatively short movement, and to equip the locomotive with mechanism whereby said movement is applied to a part of the air brake system, and also whereby said movement is applied to the throttle valve in greater proportion.

Still further objects are to provide a comparatively simple appliance capable of being used in connection with any common form of locomotive equipped with air-brake mechanism, or without the same.

With these and other objects in view, the invention consists in the novel features of construction and in the arrangement and combination of parts to be hereinafter described and particularly pointed out in the subjoined claims.

In the drawings, Figure 1 is a side elevation of a portion of a locomotive with parts thereof broken away to better illustrate my invention and the action thereof. Fig. 2 is a transverse section taken on line 2--2, Fig. 1.

Reference being had to the drawings by numerals, 3 designates a locomotive having a throttle or other controlling valve 4 by means of which the steam from the boiler is controlled in its passage to the locomotive

cylinders, whereby the driving wheels of the locomotive are caused to revolve. This throttle valve may be controlled in any suitable manner, various means being now in use, I have, however, shown the stem 5 of said valve pivotally connected to a bell crank lever 6, said lever being also pivotally connected to a rod 7 which extends out into the cab 8 of the locomotive, the rod being passed through a stuffing box 9 so as to prevent leakage of steam at the point where it projects from the boiler. The rear end of rod 9 is bifurcated, as at 10, and has pivotally secured thereto a lever 11, the pivotal point 70 being preferably between the ends of said lever. One end of the lever 11 is pivotally connected to an arm or stud 12, while its other end has pivotal connection with an actuating rod 13, as at 14. Rod 13 extends 75 forwardly and its front end is pivotally connected to an actuating lever 15 which in turn is pivotally connected at one of its ends, as at 16, to a gear segment 17. Lever 15 has a double-armed lock lever 18 pivotally secured thereto, said lock lever comprising two arms 19, 20, lying substantially parallel with lever 15 and being connected by a cross member 21 through which the pivot connecting said lock lever 85 with said actuating lever is passed. Said lock lever has one end of a lock rod 22 secured thereto, the other end thereof being adapted for engagement with the teeth of the segment 17 so as to lock the actuating 90 lever in the desired position.

23 designates the pipes of an air brake system, said pipes being connected to the usual air supply and having also connected thereto a controlling valve 24 arranged with 95 in the engine cab, said valve being adapted for manual control of the air brakes which are adapted to be pressed against the several wheels of the locomotive and those of the cars drawn thereby.

25 represents the track, and adjacent said track at various points is arranged a controlling device 26, the latter being preferably arranged so that a part thereof may be elevated and lowered as desired. For this 105 purpose it comprises a base member 27 and a top or rider member 28, the latter being supported by said base member through the medium of links 29 which are arranged parallel to each other and are inclined when 110 said top or rider member is elevated. Said top or rider member has also pivotally se-

cured thereto one end of an angle lever 30, the other end of which has an actuating rod 31 secured thereto, the angle lever being pivotally secured between its ends to the base, 5 as at 32. The actuating rod 31 may be connected with a semaphore, or with switch mechanism in any suitable manner, and when a semaphore is set against a train proceeding, the connection will be such that the 10 top or rider member of the controlling device is elevated; whereas, when the semaphore is positioned to indicate a clear track ahead, the said top or rider member will be lowered. When used in connection with a 15 switch, the connection between the actuating rod 31 and the switch mechanism will be such that when the switch is open the top or rider member will be elevated; whereas, when the switch is closed said top or rider member will be lowered. It is also to be understood that the controlling mechanism may be used independent of a switch so 20 that separate actuation of the controlling mechanism will be required. It might be here stated that opposite ends of the top or rider member 28 of said controlling device are inclined, as at 33, and also that the controlling device may be made shorter or considerably longer than herein shown.

30 In the air pipe 23 a valve 34 is arranged, said valve having a lever 35 by means of which it may be operated. To the outer end of said lever one end of a rod or link 36 is pivotally secured, said link being also pivotally secured at its other end to an actuating lever 37 pivotally secured to the locomotive between its ends, as at 38. The outer or free end of said lever 37 is bent downwardly and has a contacting roller 39 rotatably secured thereto, said roller being adapted to travel along the side of one of the rails of the track and being held sufficiently elevated so that it will not come in contact with the roadbed. This lever preferably has its pivotal connection nearer the rod or link 36 than the roller 39, as a comparatively short movement of the valve lever 35 is required to control the brakes by means of the air.

50 Pivots connected to the locomotive coincident with the pivot of the lever 37 is an angular lever 40, one end of said lever having a roller 41 rotatably mounted thereon which is also adapted to travel alongside one of the rails of the track out of contact with the roadbed. The opposite end of lever 40 has pivotally secured thereto a rack bar 42 which is preferably vertically-disposed and suitably guided, as at 43, or otherwise. This 55 rack bar is in mesh with a pinion 44 on a shaft 45 suitably journaled on the locomotive. A gear wheel 46 is also secured to said shaft and is in mesh with a horizontally-disposed gear rack 47 guided for lengthwise movement on the locomotive in any suitable

manner. Gear rack 47 is also in mesh with a pinion 48 secured to a shaft 49, said shaft having a gear wheel 50 secured thereto which is in mesh with a vertically-disposed gear rack 51 at one end of a rod 52, said rod being suitably guided for lengthwise movement and having a gear rack 53 at its upper end which is in mesh with a pinion 54. The latter is secured to a shaft 55 suitably journaled, and a gear wheel 56 is secured to said last-mentioned shaft and meshes with a horizontally-disposed gear rack 57 also suitably guided for lengthwise movement. The forward end of gear rack 57 is pivotally connected with the arm 19 of lock 80 lever 18 by a link 58, the connection between said lock lever and gear rack 57 being such that the actuating lever 15 may be manipulated without in any manner causing actuation of the automatic controlling mechanism. 85 This will at all times assure proper actuation of said actuating lever 15.

It is of course understood that the mechanism controlling the air brake system may be used independent of the mechanism controlling the steam to the locomotive cylinders; or reversely, the mechanism controlling the steam to the locomotive cylinders may be used independently of the mechanism controlling the air-brake system. 95

The operation of the device is as follows: When the top or rider member of the controlling device 26 is elevated and the locomotive passes the same, the rollers 39 and 41 are caused to ride up the rear inclined 100 end of said top or rider member and travel along said member. This causes the levers 37 and 40 to be actuated; lever 37 actuating the air valve 34 and causing the brakes to be set, while lever 40 causes the actuating lever 105 15 to be moved forwardly, which in turn closes the throttle valve 4 and shuts off the supply of steam to the locomotive cylinders. By means of the several pinions, gear wheel and gear racks interposed between lever 40 110 and actuating lever 15, the comparatively short movement of said lever 40 is imparted to the actuating lever 15 with comparatively greater range of movement, which is found necessary to properly close the throttle valve. 115 In this manner a slight elevation only of the top or rider member 28 is required, thus dispensing with unnecessary obstructions along the track. It is of course understood that when the top or rider member 28 is lowered, the rollers 39, 41 travel above and out of contact with said top or rider member. Moreover, owing to the slight rise in movement of the top or rider member, the upper surface thereof is at all 120 times in a plane or planes beneath the upper surface of the rails forming the track. It is also to be noted that when the rack bar 57 is automatically actuated it will cause the lock rod 22 to become disengaged 125 130

from the teeth of the gear segment 17 so that the actuating lever 15 is free to swing. The parts may be returned to normal position in any suitable manner. The weight 5 of the rollers 39, 41, may for this purpose be made sufficiently heavy to gravitate to normal position when passing over the inclined forward end of the controlling device 26; or this may be effected by means 10 of suitable springs, as will be apparent to any one skilled in the art to which this invention appertains.

Having thus described my invention, what I claim is,—

15 1. The combination with a locomotive having a throttle valve, a toothed segment, an actuating lever pivotally secured to said segment and mechanism interposed between said throttle valve and said actuating lever, said actuating lever having locking mechanism engaging the toothed segment to maintain said lever in adjusted position, of a controlling device arranged adjacent the track, a longitudinally-disposed rack bar lengthwise movable, a link connecting said bar with said locking mechanism, a contact device adapted to engage said controlling

device, and gear and rack connections between said contact device and said rack bar.

2. The combination with an actuating lever for controlling steam to the locomotive cylinders, of a horizontally-disposed rack bar connected to said actuating lever, a gear wheel engaging said rack bar, a pinion rotatable with said gear wheel, a vertically-disposed bar having a gear rack at its upper end engaging said pinion and having also a gear rack at its lower end, a gear wheel engaging said last-mentioned gear rack, a pinion rotatable with said last-mentioned gear wheel, a horizontally-disposed gear rack engaging said last-mentioned pinion, a gear wheel engaging said last-mentioned gear rack, a pinion rotatable with said last-mentioned gear wheel, a vertically-disposed gear rack engaging said last-mentioned pinion, and a lever pivotally connected between its ends and having pivotal connection at one end with said last-mentioned gear rack, said lever having a contact roller 50 at its other end adapted to engage a controlling device arranged alongside the track.

In testimony whereof I affix my signature.

DANIEL A. TRACY.
